UNITED STATES PATENT OFFICE.

WILLIAM R. KINNEAR, OF COLUMBUS, OHIO.

METALLIC DOOR.

SPECIFICATION forming part of Letters Patent No. 445,262, dated January 27, 1891.

Application filed February 14, 1890. Serial No. 340,398. (No model.)

To all whom it may concern:

Be it known that I, WILLIAM R. KINNEAR, a citizen of the United States, and a resident of Columbus, in the county of Franklin and

5 State of Ohio, have invented new and useful Improvements in Iron Structures, of which the following is a full and exact description, reference being had to the accompanying drawings, making part of this specification.

10 This invention relates to improvements in metallic doors; and it consists in the novel construction and arrangement of the parts hereinafter more fully set forth and claimed.

15 It is the object of this invention to produce a metallic door which will be light and suitable for use in the finished structure, such as dwelling houses, hotels, &c.

20 In the accompanying drawings, Figure 1 is a perspective view of a door constructed in accordance with this invention. Fig. 2 is a detail view in perspective of an upper corner of the door. Figs. 3, 4, and 5 are detail views in section of the successive steps in forming the joint of the parts of the door.

25 The door shown in the drawings is formed in two continuous sections A and B of very light sheet metal, each section forming the entire surface of one side of the door, and the design of panels or other figures is pressed 30 into the metal in such way as to produce the rails C, which are provided to strengthen the construction and prevent buckling or twisting therein, thus rendering it possible to use the lighter grades of material. These sections are provided with raised flanges A' and 35 B' set up from their sides to form the edge of the door and a joint between the sections.

To form a smooth surface at the corners of the door the flanges are rounded, as shown at 40 Fig. 2 of drawings. In this form the accumulated material incident to the formation of a corner in metal is distributed around the area of the curve instead of being crowded into a square corner. This allows for the 45 formation of a comparatively smooth surface on the corners by pressing the metal and compelling it to distribute itself more or less evenly around the corners. To make a yet smoother surface at these points after thus 50 forming them I proceed to dress them with a file. Before thus turning up the flange A'

its outer edge is set back to form the extension a, the purpose of which is to form a joint in conjunction with the flange B' on the section B.

55 Previous to joining the sections the section A is filled with some material D, such as loose asbestos, mineral wool or like substances to render the structure solid and durable, and prevent the transmission of sound through 60 the door. In some instances I use for a filling a wooden frame, which fills in the rails C and helps to strengthen the construction, and in cheaper work renders the application of hinges and other door furnishings easier by 65 accommodating the use of wood-screws instead of the bolts or metal screws which are used in the other constructions. When the section A is filled, as above stated, section B is placed upon it, with the flange B' extending 70 up over the extension a, as shown at Fig. 3. The sections are now joined by turning the flange B' down upon the extension a on all sides, as shown at Fig. 4, and then turning the folded flange and extension into the recessed part of the extension to form the double 75 loop-joint shown at Fig. 5. Care is taken in this last operation to bring the outer surface of the joint to a flush surface with the flange A', in order to present an even surface on the 80 edge of the completed door. This folded joint has the appearance of an edging-bead, such as is used in wood constructions.

85 The door furnishings may be attached to the structure in any of the ordinary ways. When the door is mortised, care is taken to leave an edging of metal that may be turned into the mortise.

Having thus described my invention, what I claim is—

90 1. As a new article of manufacture, a door composed of sheet-metal sections, each forming the one side of the door, and flanges A' and B', curved at the corners of the door and connected by a double-fold joint, substantially as 95 described.

2. As a new article of manufacture, a door composed of sheet-metal sections, each forming the one side of the door, flanges A' and B', turned up from the said sections and 100 curved at the corners of the door, and a double-loop connection formed by the flange

B' and extension *a*, to join the said sections and form an edging-bead, substantially as described.

3. As a new article of manufacture, a door composed of sheet-metal sections A and B, each forming the one side of the door and provided with strengthening-rails C, flanges A' and B', joined at their meeting edges and curved at the corners of the door, and a fill-

ing D between the said sections to render the construction solid, substantially as described.

In testimony whereof I have hereunto set my hand this 15th day of January, A. D. 1890.

WILLIAM R. KINNEAR.
